UNITED STATES PATENT OFFICE.

JOHN GRAHAM, OF CHICAGO, ILLINOIS, ASSIGNOR TO MARDER LUSE & CO., OF SAME PLACE.

DESIGN FOR A FONT OF TYPE.

SPECIFICATION forming part of Design No. 15,237, dated August 12, 1884.

Application filed June 21, 1884. Term of patent 3½ years.

To all whom it may concern:

- Be it known that I, JOHN GRAHAM, a citizen of the United States, residing at Chicago, in the county of Cook and State of Illinois, have invented and produced a new and original Design for a Font of Printing-Type, of which the following is a specification, reference being had therein to the accompanying drawing.
- 10 My invention consists of a new design for a font of printing-type having the peculiarly-formed letters and figures shown in the accompanying printed specimens and hereinafter described.
- 15 The beginning and terminal ends and the upper and base lines of most of the capitals and small letters are tapered to a fine sharp point. The capital letters A, D, E, F, and Z and small letter a have angular top lines inclined obliquely downward to the left and right from the angle. The cross central stroke of the letter A is angular and disconnected from the left line of the letter. The capital letters B P R and one form of letter D have their top lines inclined obliquely upward from the left side of the letters. The letters E, L, and Z have angular lower lines inclined obliquely upward right and left from the angles. The capital letter G has an oblique line across the lower curve. The central line of the capital letter H is angular and disconnected from the right vertical line of the letter. The top of J is formed with a long horizontal line. The letter M has an angular oblique line disconnected from the left portion of the letter. The top of the left vertical line of K and of V has a line inclined upward to the left, terminating in a fine point. The tops of the letters L and M, the left line of W, and the right line of N and Y are inclined obliquely upward to the right and terminate in fine points. The lower portion of Y terminates in a tapered line inclined obliquely downward to the right. The tops of the stems of the small letters b and d are formed with horizontal cross-lines. h has the upper horizontal cross-line, and the upper line of the right portion is angular and disconnected from the stem. The top of the upper portion of the small letter k is formed with a backward scroll. The upper lines of the right portions of the letters m and n are angular and disconnected from the left portions of these letters. One of the oblique lines of the small letter x is formed in two angular parts disconnected from the other portion of the letter. The figures 1, 2, 3, 4, and 5 have a tapered pointed finish, as shown. The upper portion of the figure 8 is angular and terminates with downward left oblique lines. The ends of the lines forming the character & are angular and disconnected.
- 20 I claim—
- 25 The new design for a font of printing-type, as herein set forth, and as shown in the printed specimens.
- 30 In testimony whereof I affix my signature in presence of two witnesses.
- 35 JOHN GRAHAM.
- Witnesses:
- 36 JAMES HAWKINS,
GEO. E. SAVAGE.
